UNITED STATES PATENT OFFICE

170,240

FITTING FOR TUBULAR STRUCTURES

Walter Raylor, Englefield Green, England, assignor of one-half to Alumasc Limited, London, England, a British company

Application March 11, 1952, Serial No. 18,852
In Great Britain September 12, 1951

Term of patent 14 years

(Cl. D54—2)

To all whom it may concern:

Be it known that I, Walter Raylor, a British subject, citizen of the United Kingdom and Colonies, residing at "Northroyd," Crimp Hill, Englefield Green, Surrey, England, have invented a new, original, and ornamental Design for a Fitting for Tubular Structures, of which the following is a specification, reference being had to the accompanying drawing forming a part thereof.

Fig. 1 is a side perspective view of a fitting for tubular structures, showing my new design;

Fig. 2 is a perspective view thereof showing the side opposite Fig. 1; and

Fig. 3 is a bottom plan view.

I claim:

The ornamental design for a fitting for tubular structures, as shown.

WALTER RAYLOR.
